UNITED STATES PATENT OFFICE.

EDGAR A. BAUGHAN, OF ATLANTA, GEORGIA.

DESIGN FOR A BADGE, BUTTON, EMBLEMATIC CAP, OR ARTICLE OF SIMILAR NATURE.

Application filed January 13, 1922. Serial No. 189. Term of patent 14 years.

To all whom it may concern:

Be it known that I, EDGAR A. BAUGHAN, a citizen of the United States, and a resident of Atlanta, county of Fulton, State of Georgia, have invented a new, original, and ornamental Design for a Badge, Button, Emblematic Cap, or Article of Similar Nature, for which the following is a specification.

Referring more particularly to the accompanying drawing:

The figure is a face view of the design shown applied to a cap, which is illustrated in dotted lines.

The dominant features of my design, as

shown in the drawings, consist of a head executed in high relief, adorned by an ornamental head dress, mounted upon a star, which latter rests upon a crescent with its two lower points overlapping the points of the crescent.

I claim:

The ornamental design for a badge, button, emblematic cap, or article of similar nature, as shown and described.

EDGAR A. BAUGHAN.
